Patented Mar. 2, 1976

239,046

EAR WIRE

Ralph Pintarelli, 600 Manton Ave.,
Providence, R.I. 02909

Filed Feb. 4, 1974, Ser. No. 439,593

Term of patent 14 years

Int. Cl. D11—01

U.S. Cl. D45—9

FIG. 1

FIG. 2

FIG. 3

FIG. 4

FIG. 5

FIG. 1 is a front elevational view of an ear wire showing my new design;

FIG. 2 is a top plan view thereof;

FIG. 3 is a bottom plan view thereof;

FIG. 4 is an end view looking from the right with respect to FIG. 1; and

FIG. 5 is an end view looking from the left with respect to FIG. 1.

I claim:

The ornamental design for an ear wire, substantially as shown.
